UNITED STATES PATENT OFFICE.

DANIEL M. TUTTLE, OF CANASTOTA, NEW YORK, ASSIGNOR TO STELLA S. TUTTLE, OF CANASTOTA, NEW YORK.

INTERNAL-COMBUSTION ENGINE.

1,127,322.

Specification of Letters Patent.

Patented Feb. 2, 1915.

Application filed November 17, 1911. Serial No. 660,834.

To all whom it may concern:

Be it known that I, DANIEL M. TUTTLE, of Canastota, in the county of Madison, in the State of New York, have invented new and useful Improvements in Internal-Combustion Engines, of which the following, taken in connection with the accompanying drawings, is a full, clear, and exact description.

10 This invention relates to certain improvements in internal combustion engines of the two-cycle multi-cylinder type, somewhat similar to that set forth in my pending application No. 644,760, filed August 18, 1911, in which the primary object is to extend the interval of time during which the explosive mixture will continue to flow into the explosion chamber of each cylinder beyond that during which the exhaust port is 20 open, or rather, after the exhaust port is closed by the piston during its compression stroke, for the purpose, not only of admitting and compressing a larger charge of the explosive mixture under relatively low speeds, but also of maintaining a relatively large charge, and complete cleansing of the cylinder at each cycle of operation under relatively high speeds, thereby materially increasing the power efficiency of the engine 30 under all speeds.

One of the specific objects of my present invention is to direct the inflowing mixture across or in the immediate vicinity of the terminals of the spark plug, so as to assure 35 greater reliability in the firing of each charge, or rather to reduce the liability to miss firing at the end of each compression stroke of the piston.

Another important object is to provide 40 the interior of the head end of the combustion chamber with a deflecting wall located in the path of the inflowing mixture for the purpose of diverting such inflowing mixture transversely of the cylinder, thereby more 45 effectively cleansing the cylinder from spent gases, and at the same time increasing the combustibility of the mixture within the sphere of the sparking terminals.

Another object is to simplify the valve 50 control for the inflowing mixture by reducing the number of valves to a minimum and avoiding the interposition of a valve between the cylinders and controlling the initial entrance of the mixture from the carburetor to the cylinder by means of a valve

located at the outside of the cylinder proper where it is easily accessible for repairs or adjustment without interfering with any of the other parts of the engine.

Other objects and uses will be brought out in the following description.

In the drawings—Figures 1 and 2 are longitudinal vertical sectional views of my improved engine, taken at right angles to each other. Figs. 3, 4 and 5 are horizontal sectional views taken respectively on lines 3—3 and 4—4, Fig. 1, and 5—5 Fig. 2, considering the engines in their entirety rather than in section. Figs. 6 and 7 are vertical sectional views taken respectively on lines 6—6, Fig. 1, and 7—7, Fig. 2. Fig. 8 is a detailed sectional view of the upper portion of a pair of slightly modified form of cylinders, showing rotary valves instead of puppet valves. Fig. 9 is a sectional view taken on line 9—9. Fig. 8, considering this portion of the engine in its entirety. Fig. 10 is a vertical sectional view of a slightly modified form of engine for which rotary valves for the intake and inlet together with the bypass are located in a separate valve case or attachment to the side of the cylinders, while the spark plug is located at one side of the center at the head of the cylinder with its spark terminals in the inlet. Fig. 11 is a sectional view taken on line 1—11, Fig. 10.

As shown in Figs. 1 to 7 inclusive, this engine comprises duplicate juxtaposed cylinders 1—1' and 1—1', preferably of cast metal integrally united, provided with combustion chambers 2—2 and 2—2' and compression chambers 3—3 and 3—3' for receiving reciprocating pistons 4—4 and 4—4', as best seen in Figs. 1 and 2, said pistons being connected by pitmen 5—5 and 5—5' to diametrically opposite crank arms 6—6 and 6—6' of a crank shaft 7—7. The combustion chamber and compression chamber of each cylinder are coaxial but of unequal diameters, the compression chamber being located at the outer end of the combustion chamber, and is of sufficiently larger diameter than that of the combustion chamber so that its excess area equals or exceeds the cross sectional area of said combustion chamber. In like manner the inner and outer ends of the pistons 4—4 and 4—4' are of different diameters, the diameter of each smaller portion being

substantially equal to that of the combustion chamber, while the diameter of its outer end is substantially equal to that of the compression chamber in which it is 5 adapted to move, and is adapted to coact with the head of the compression chamber to receive and compress a larger charge or quantity of the explosive mixture than could be admitted and compressed in the 10 combustion chamber at the smaller end of the piston. This coaction of the enlarged portion of the piston with the head of the compression chamber also provides a higher degree of compression of the explosive mixture than could possibly be produced if the 15 mixture were admitted to the crank case and compressed therein by the down stroke of the piston. The inner ends of the compression chambers —3— and —3'— are provided with intake ports —8— and —8'— communicating with the interior of a valve case —9—, in which is movable coaxial rotary valves —10— and —10'—, said valve case being provided with a fuel inlet —11—, 20 common to both valves and communicating with a suitable mixing chamber —12— of a carburetor or equivalent device. The valve case —9— is also provided with a pair of branch ports —13— and —13'—, one for 25 each of the cylinders —1— and —1'—, and communicates with a single by-pass or chamber —14—, which in this instance is located between the cylinders and communicates, through branch passages —15— and —15'—, with fuel inlet ports —16— and —16'— in the heads of the combustion chambers —2— and —2'— of the cylinders. These ports —16— and —16'— are opened 30 and closed by means of puppet valves —17— and —17'—, which in this instance are located centrally in the heads of the combustion chambers and are automatically closed by suitable springs —18— when the pressures at opposite sides of the valves are substantially equal, such springs and the stems 35 of the valves being protected by shields or screw caps —19— in the heads of the cylinders. Each of the cylinders is also provided with an exhaust port —20—, communicating with the outer end of the combustion chamber in proximity to the limit of the outward movement of the inner end of the corresponding pistons, and are controlled by such pistons. Each of the valves 40 —10— and —10'— is provided with a pair of diametrically opposite recesses or cutouts —21— and —21'—, those of each pair being disposed at substantially right angles to those of the other pair for alternately connecting the compression chambers of the cylinders with the fuel mixing chamber —12— and distributing chamber —14— which leads to the combustion chambers of 45 said cylinders. These valves are connected for simultaneous rotation at substantially

half the speed of the crank shaft and are timed so that when each piston reaches the limit of its outward stroke, the corresponding valve will have just closed communication between the mixing chamber and compression chamber and will also have closed communication between the compression chamber and distributing chamber —14— as shown more clearly in Fig. 2, while the other valve corresponding to the other piston which is at the limit of its compression stroke will be in a different position at substantially right angles to the first named valve to also close communication between the compression chamber of that cylinder and the mixing chamber —12— and the distributing chamber —14—. These valves are rotated in the direction indicated by arrow —x— and may be driven by any suitable power transmitting mechanism connected to a rotary part of the engine, as, for example, the crank shaft —7— and for this purpose I have provided said crank shaft with a sprocket wheel —25— which is connected by a chain —26— to a somewhat larger sprocket wheel —27— on the protruding end of a shaft —28— carrying the valves —10— and —10'—, the ratio of the sprocket wheels —25— and —27— being in this instance one to two. Now assuming that one of the pistons as —4— is in its extreme outward position as shown in Fig. 2 to open the corresponding exhaust port —20— and that the other piston is at the limit of its inward or compression stroke and that a charge of the explosive mixture has been drawn into the compression chamber —3— through the intake port —8—, then, shortly after the piston —4— begins its inward stroke, the corresponding valve —10— will have been rotated in the direction indicated by arrow —x— sufficiently to open communication between the intake port —8— and distributing chamber —14—, thereby connecting the compression chamber —3— with the combustion chamber —2— through the passage —15— and valve port —16—, it being understood that when the piston is in this extreme outward position with the exhaust port —20— opened, the pressure on the inner side of the valve —17— is less than that upon the outer side of the valve, thereby opening said valve to admit the explosive mixture to the corresponding combustion chamber —2— so that as the piston continues its inward stroke even after closing the exhaust port —20—, the explosive mixture in the compression chamber will be compressed and forced through the port —8— and open valve —10— to the distributing chamber —14— and thence through the passage —15—, thereby producing a gradually increasing pressure upon the outside of the valve —17— in excess of the pressure on the inner side of the valve —18—.

to hold said valve open for a considerable period of time after the port —20— is closed by the piston or until the pressure upon the inner side of the valve is equal to or exceeds that upon the outer side of the valve, whereupon said valve —17— will be closed and the mixture in the explosion chamber will be further compressed during the remainder of the inward stroke of the piston. In practice, it is found that this excess pressure on the outer side of the valve will continue during nearly half the inward stroke of the piston by which time the other piston —4— will have been moved outwardly substantially half its full stroke by the explosion of the mixture in the combustion chamber —2'—, and owing to the expansive force of the exploded mixture in the combustion chamber —2'— and consequent increased pressure on the inner side of its corresponding valve —17'—, this increased pressure will continue to hold the valve —17'— closed against the pressure in the corresponding passage —15— tending to open said valve until nearly the time of opening of the corresponding exhaust port —20'—. As soon as the exhaust port —20'— is opened, the pressure in that cylinder will be reduced to atmosphere, thereby allowing the excess pressure in the passage —15'— to open the valve —17'— and thereby admit the explosive mixture to the combustion chamber —2'—, it being understood that during the outward movement of the piston —4'—, the corresponding valve —10'— will open communication between the compression chamber —3'— and mixing chamber —11—, thereby drawing in a fresh charge of the mixture into the compression chamber —3'— ready to be compressed by the upstroke of the same piston. At this time the first named piston —4— will have reached the limit of its upward or compression stroke to compress the charge of explosive mixture in the combustion chamber —2— which is then ignited and operates to drive the piston —4— outwardly during which the opposite piston —4'— is moved upwardly and its corresponding valve —10'— will open communication between its compression chamber —3'— and combustion chamber —2'—. As the piston —4— continues its downward movement its corresponding valve —10— will open communication between the compression chamber —3— and mixing chamber —11— to permit the piston —4— to draw in a fresh charge of the mixture into said compression chamber, the same valve serving to cut off communication between said compression chamber and combustion chamber of the corresponding cylinder and as soon as or slightly before the exhaust port —20— begins to open, the valve —17— will be opened by the excess of pressure of the mixture in the

passage —15—, thereby admitting the explosive mixture to the combustion chamber —2— ready for compression upon the upstroke of the corresponding piston.

Another important feature of my invention consists in providing the head end of each cylinder with a deflector —29— located at one side of but in proximity to the corresponding ports —16— and —16'— in the path of the inflowing mixture for the purpose of deflecting such mixture laterally or transversely of the combustion chamber immediately upon its entrance thereto.

A further important feature of my invention consists in locating the ignition terminals of the spark circuit in the path of the inflowing mixture, and for this purpose I have shown a spark plug —30— as screwed in the head of the cylinder in such manner that its terminals lie in the paths of the inflowing mixture in close proximity to the ports —16— and —16'— and in this instance between said ports and their deflectors —29— so that at least a portion of the mixture must pass across the spark terminals, thereby assuring greater certainty in the firing of each charge at the proper time. In some instances, however, I may prefer to use rotary valves instead of puppet valves in controlling the entrance of the explosive mixture to the combustion chambers and in Figs. 8 and 9 I have shown a rotary shaft or spindle —32— as journaled centrally in the heads of cylinders —33— and —33'— and provided with valves —34— and —34'— for opening and closing adjacent ports —35— and —35'— in the heads of said cylinders, said valves also serving to open and close additional ports —36— and —36'— which communicate with a distributing chamber —37— forming a part of a chamber —14'— which leads to the valve ports —13— and —13'— of the valve case —9—. This valve shaft —32— may be driven from any suitable rotary part of the engine and for this purpose is provided with a sprocket wheel —38— which is connected by a chain —39— to a similar sprocket wheel —40— on the shaft —28— so as to rotate at the same speed as the last named shaft. The valves —34— and —34'— are formed by providing the shaft —32— with diametrical openings therethrough arranged at substantially right angles to each other so that when the ports corresponding to one valve are opened, those corresponding to the other valve will be closed and vice versa.

In Figs. 10 and 11 I have shown a double cylinder internal combustion engine somewhat similar to that shown in Figs. 1 and 2 except that rotary valves are employed for controlling communication between the compression chamber and mixing chamber and also between the distributing chamber and combustion chamber and that these rotary

valves and distributing chamber are arranged in a separate casting —41— secured to one side of the cylinders as best seen in Fig. 10. That is, the casting —41— is provided with a distributing chamber —41'— located at one side of the cylinders instead of between them as shown in Figs. 1 and 2, the adjacent side of the cylinder forming a part of one side of the distributing chamber 10 and communicates at its lower end with ports —13— and —13'— which are opened and closed by the valves —10— and —10'— in substantially the same manner as shown in Figs. 1 to 7 inclusive. The opposite or 15 upper ends of the distributing chamber communicate with suitable ports —42— of a valve case —43— in which is movable rotary valves —44— similar to the valves —34— and —34'— shown in Fig. 8, said valve casting —43— being provided with additional ports —45— communicating with the combustion chambers of their respective cylinders. In this instance the spark plugs —30— are secured in the heads of the cylinders with their terminals projecting into their respective ports —45— in the paths of the inflowing mixtures so as to assure greater reliability in igniting the mixture at the proper time, the valve —43— being 20 driven in substantially the same manner as shown in Fig. 8. By making the casting —41— separate from the main body of the engine, I am enabled to cast the parts more perfectly or with less liability of imperfections and at the same time this arrangement permits the use of the spark plug directly in the port leading to the combustion chamber in the path of the inflowing mixture so as to reduce the liability of missfire. Otherwise aside from the necessity for making a 25 tie joint between the casting —41— and adjacent side of the engine, the construction is similar to that shown in Figs. 1 to 7 inclusive and the operations of both devices 30 are similar in effect.

What I claim is:

1. In a two-cycle internal combustion engine, a pair of cylinders each having a combustion chamber and a compression chamber of larger diameter than the combustion chamber, each combustion chamber having an inlet port in one end and an exhaust port in its opposite end, intake ports for the compression chambers, a single bypass connecting the intake ports to the inlet ports of both cylinders, co-axial rotary valves controlling communication between the intake ports and bypass and located at one and the same side of the cylinders, and additional valves controlling communication between the bypass and inlet ports.

2. In a two-cycle internal combustion engine, a pair of cylinders each having a combustion chamber and a compression chamber of larger diameter than the combustion

chamber, each combustion chamber having an inlet port in one end and an exhaust port in its opposite end, intake ports for the compression chambers, a single bypass connecting the intake ports to the inlet ports of both cylinders, co-axial rotary valves controlling communication between the intake ports and bypass and located at one and the same side of the cylinders, additional valves controlling communication between the bypass and inlet ports, and deflector plates projecting inwardly from the head ends of the cylinders partially across their respective combustion chambers in the path of the inflowing mixture through the inlet ports.

3. In a two-cycle internal combustion engine, a pair of cylinders each having a combustion chamber and a compression chamber of larger diameter than the combustion chamber, the combustion chamber having an inlet port in one end and an exhaust port in its opposite end, intake ports for the compression chambers, a single bypass connecting the intake ports to the inlet ports of both cylinders, co-axial rotary valves controlling the communication between the intake ports and bypass and located at one and the same side of the cylinders, additional valves controlling communication between the bypass and inlet ports, and spark plugs having their terminals disposed in the path of the inflowing mixture through the inlet ports.

4. An internal combustion engine comprising a plurality of cylinders each having a combustion chamber and a co-axial but larger compression chamber, each combustion chamber having an inlet port and an exhaust port, while each compression chamber is provided with an intake port, pistons movable in the combustion chambers and provided with compression heads movable in the compression chambers, a single distributing chamber connecting the intake ports to the inlet ports, co-acting rotary valves controlling the supply of fuel through the intake ports and also from the intake ports to the distributing chamber, and additional valves controlling the passage of the mixture from the distributing chamber through the inlet ports.

5. In an internal combustion engine, a cylinder, a compound piston working within the cylinder and cooperating therewith to form a combustion chamber and a pumping chamber, means for conducting a gaseous fluid from a source of supply to the pumping chamber and from the pumping chamber to the combustion chamber, a valve operable to open communication between the source of fluid supply and the pumping chamber during a portion of the movement of the piston and to open communication between the pumping and combustion chambers during another portion of the movement of the piston, and a second valve oper-

able to open communication between the pumping and combustion chambers during a portion of the movement of the piston.

6. In a multiple cylinder two-cycle engine, a charge distributing chamber common to all of the cylinders, a piston working in each cylinder, a rotary valve common to all of the cylinders and coöperating with the several pistons to effect a pumping of charges from a source of supply into said chamber, rotary means for controlling the admission of charges to the combustion ends of the cylinders from said chamber, and means for driving said valves.

15 7. In a multiple cylinder two-cycle engine, a charge distributing chamber common to all of the cylinders, pistons working in the cylinders and having parts coöperating therewith to form pumping chambers, a rotary valve for controlling the admission of gas to the pumping chambers from a source of supply during a movement of the respective pistons in one direction and the inlet of gas to the distributing chamber during a movement of the pistons in the opposite direction, a rotary valve for controlling the admission of charges to the combustion ends of the cylinders from the distributing chamber, and means for driving said valves.

20 8. In a multiple cylinder internal combustion engine having its cylinders provided with pumping and combustion chambers, a charge distributing chamber common to all of said chambers, a rotary valve for control-

ling the admission of charges to the pump- 35 ing chambers from a source of supply and from the pumping chambers to the distributing chamber, a rotary valve for controlling the distribution of charges to the combustion chambers from said distributing 40 chamber, and means for driving said valves in unison.

9. In an internal combustion engine, a cylinder, a compound piston working within the cylinder and coöperating therewith to 45 form a combustion chamber and a pumping chamber, means for conducting a gaseous fluid from a source of supply to the pumping chamber and from the pumping chamber to the combustion chamber, a rotary 50 valve operable to open communication between the source of fluid supply and the pumping chamber during a portion of the movement of the engine and to open communication between the pumping and combustion 55 chambers during another portion of the movement of the engine, and a second rotary valve operable to open communication between the pumping and combustion chambers during a portion of the movement 60 of the piston.

In witness whereof I have hereunto set my hand on this 11th day of November, 1911.

DANIEL M. TUTTLE.
